UNITED STATES PATENT OFFICE.

EDWIN LEONARD SMALLEY, OF EAST ORANGE, NEW JERSEY.

ELECTRIC FURNACE.

1,346,854.

Specification of Letters Patent. Patented July 20, 1920.

Application filed October 21, 1919. Serial No. 332,261.

To all whom it may concern:

Be it known that I, EDWIN L. SMALLEY, a citizen of the United States, and resident of East Orange, in the county of Essex and 5 State of New Jersey, have invented certain new and useful Improvements in Electric Furnaces, of which the following is a specification.

This invention relates to electric furnaces, 10 and it comprises a modification of the furnace structure illustrated in my earlier Patent No. 1234499, embracing improvements having special relation to furnaces unlimited as to their size, which require the use of 15 a considerable number of refractory plates, resistance conductors, and supports therefor.

Especially in the larger sized furnaces, it 20 may be desirable, as in the event of breakage of a refractory plate, or in the event of the resistance conductors requiring replacement, or where it may be expedient to localize the heat at one or more given regions in the furnace, to be able to remove and replace 25 certain of the refractory plates or resistance conductors, or to adjust their positions longitudinally through the furnace.

Therefore, my invention includes the provision of refractory plate supports which 30 may be in the form of rail sections or tiles, suitably mounted in longitudinal reception grooves therefor in the bricking of the furnace arch and sides, said supports being movable along their reception grooves in 35 order that they may be shifted out of supporting relation with any refractory plate or plates to be removed, or whereby said supports may be adjusted to suitable positions along the furnace, at which they are 40 to exercise their function of supporting the refractory plates. By these means, refractory plates may be conveniently removed from and replaced within the furnace with great convenience, for such purposes as renewal, or replacing of resistance conductors, 45 and also the heating effect within the furnace may be adapted to answer any special localized heating conditions with respect to the furnace.

50 The resistance conductors, which, as in my said earlier patent, lie in grooves at the reverse side of the refractory plates, may extend out through the rear wall of the furnace when said resistance conductors are 55 continuous throughout the length of the furnace; or, where each or some of the re-

fractory plates carry individual resistance conductors, the terminals thereof may extend out through the arch or upper portion of the furnace, or out through the side walls 60 of the furnace to there connect with collector means.

Other features and advantages of my invention will hereinafter appear.

In the drawings: 65
Figure 1 is a cross-sectional elevation of my improved furnace.

Fig. 2 is an enlarged detail, partly in section, showing the adjustable supporting means for the refractory heating units. 70

Fig. 3 is a side elevation of the same on a smaller scale, and Fig. 4 shows a modification.

In the example of furnace with which my improvements are employed, herein illustrated, let 1 indicate the external frame elements, 2 the interior brick lining composed of material which is a non-conductor of heat, filling material, of usual character in this art being provided between the frame 75 elements and the lining. I have shown the upper portion of the furnace as arched, to add strength thereto.

As is the case with my earlier Patent No. 1234499, I intend the interior wall surfaces 85 to carry heating units composed of refractory plates and resistance conductors, but, since the larger size of furnace which is contemplated in the present application requires the employment of a number of heating 90 plates, in order that they may be renewable, in case of breakage, or removable for other purposes, and adjustable to permit the provision of localized heat regions within the furnace, I therefore provide a 95 novel form of supporting means for said heating plates, and arrange said supporting means in such relation with respect to the furnace that they will possess the characteristic features necessary to enable them to 100 satisfy the stated requirements.

Thus, the upper and side surfaces of the furnace are provided with longitudinal, approximately T-shaped grooves or channels 105 3, which may extend in parallelism throughout the length of the furnace, and within these grooves are placed a number of refractory-plate supports 4, which are approximately rail shaped in cross-section, so that one head portion of each such support 110 lies within its T-shaped groove, and the opposite head portion of the rail shaped sup-

port projects from the groove interiorly of the furnace, to there present a portion of its web and said opposite head portion as supporting means for a heating plate.

5 The grooves 3, for convenience of production, may be formed in two halves respectively in opposed surfaces of adjacent lining bricks 2, and the supports 4, which may be of tile, are loosely fitted in said 10 grooves, to be capable of adjustment therein longitudinally with respect to the furnace. Slidably fitting between the shanks or webs of adjacent parallel supports 4, and retained by the exposed heads of said supports which 15 project within the furnace, are the heating units each consisting of a plate 5, having on its reverse surface a series of parallel grooves 6 containing a resistance conductor 7, said conductor being here shown as a 20 heavy duty resistor of relatively stiff, unbending character, pre-shaped in the form of a return bend coil whose strands are to be lodged in the grooves of the plate, as in my said earlier patent. The plates 5 may 25 lie in supported relation by the supports 4 longitudinally of the furnace with their end edges in close proximity or separated by intervening spaces of any desired extent, to furnish heating temperature, either diffused 30 or localized as desired to suit the particular heat conditions for which the furnace is to be used. Also the resistance conductor 7 may be of continuous length throughout the longitudinal extent of the furnace, in which 35 event its terminals may be caused to project through the rear wall or side walls thereof, or said resistance conductor may be individual to a plate 5, when its terminals may be carried through either the top or sides of 40 the furnace, as at 9, to communicate with a bus bar as at 10.

In Fig. 1 refractory plates 11 shown in the bottom of the furnace obviously require no means of support such as 4. I use such 45 additional bottom heating units to complete the surrounding heating surfaces required. I may also employ floor plates 12 of a vitrified material to resist the abrasive wear incurred in loading and discharging the furnace.

50 A particular feature of the invention however resides in the slidable arrangement of the supports 4 within their grooves, with endwise spacing, so that they can be slid 55 into different positions lengthwise of the furnace, since, by these means, the heating units may be adjusted as to their positions, and if desired, a refractory plate may be removed by sliding its support or supports 60 apart sufficiently to leave a clearance between supports to permit the removal of a refractory plate from between the ends thereof, and also to permit a refractory plate to be inserted intermediately of a line of 65 plates without requiring withdrawal outside

the furnace of the forward plates. When it is realized that the furnace may have considerable length, as for example 12 feet, which I have constructed and have in successful operation, using a number of lengthwise adjustable refractory plates, the convenience of this slidably adjustable arrangement of the supports will be appreciated. 70

The front cover or door of the furnace is not herein illustrated, because it is of usual 75 character, and presents no novel feature.

Obviously, I might construct a furnace having inverted grooves 13 in the arch bricks 2 (see Fig. 4) corresponding to the grooves in refractory plates 6, and then use plain 80 flat plates 14 in place of grooved plates 5. But I prefer the arrangement of grooved plates and flat face bricks as detailed on account of consequent ease in replacement of component parts. 85

Variations may be resorted to within the spirit and scope of my invention and parts thereof used without others.

I claim:

1. The combination, with an electrical furnace having a series of heating units, of horizontally shiftable supporting elements within said furnace for said heating units whereby the latter are rendered both adjustable and renewable. 90

2. The combination, in an electrical furnace, of a series of refractory plates therefor, including resistor elements, and horizontally shiftable supporting members within said furnace for said plates, whereby the 100 latter are rendered both adjustable and renewable.

3. The combination, in an electrical furnace, having heating plates, of an interior surface of said furnace provided with 105 lengthwise grooves, and series of support units longitudinally slidable within said grooves, whereby parallel pairs of said support units are capable of removably supporting heating plates. 110

4. In an electrical furnace, having heating plates, in combination, a housing, the inner surface of said housing having parallel longitudinal grooves, support units adjustably slidable in engagement with said 115 grooves, and means upon said support units whereby a parallel pair thereof are capable of removably supporting a heating plate.

5. In combination, an electrical furnace whose interior surface is provided with 120 lengthwise grooves, spaced apart in parallelism, series of lengthwise adjustable support units slidably engaged in said grooves, said support units having projecting portions, and series of heating plates, having resistor elements, said heating plates respectively being in slidable engagement with opposite projecting portions of parallel support units. 125

6. In combination, an electrical furnace 130

whose interior surface is provided with lengthwise grooves, each approximately T-shaped in cross-section, spaced apart in parallelism, series of lengthwise adjustable support units, each approximately rail shaped in cross-section, engaged by one head portion in a groove, and heating plates, hav-

ing resistor elements, engaged between parallel pairs of said support units by their other head portions.

10

Signed at the borough of Manhattan, in the city, county, and State of New York, this 30th day of September, A. D. 1919.

EDWIN LEONARD SMALLEY.
